UNITED STATES PATENT OFFICE

HENRY ROBERT MARSH, OF WALTHAM, MASSACHUSETTS, ASSIGNOR TO SACO-LOWELL SHOPS, OF BOSTON, MASSACHUSETTS, A CORPORATION OF MASSACHUSETTS

TWISTER FRAME

Application filed March 18, 1931. Serial No. 523,417.

This invention relates to twister frames and is more especially concerned with that type of frame in which the twisting operation is performed in two successive steps or in which two banks of spindles are used, one located at a higher level than the other.

It is the chief object of the invention to improve the operating mechanism for the spindles of machines of this type with a view to facilitating the control of the spindles and simplifying the driving mechanism.

The nature of the invention will be readily understood from the following description when read in connection with the accompanying drawings, and the novel features will be particularly pointed out in the appended claims.

In the drawings,

Figure 1 is a vertical, sectional view, somewhat diagrammatic in character, illustrating a twister frame embodying features of this invention;

Fig. 2 is a plan view of the spindle driving mechanism indicated in Fig. 1; and

Figs. 3 and 4 are plan views illustrating additional spindle arrangements.

Referring first to Figs. 1 and 2, the arrangement there shown comprises two upper spindles 2 and 3, respectively, and two lower spindles 4 and 5. The individual members of each of these pairs of spindles are located at opposite sides of the machine frame from each other. Each of the upper spindles is designed to support a spool or other yarn body or package from which the supply of yarn, thread, or other material to be twisted (hereinafter referred to as yarn) is drawn. Referring first to the units at the right-hand side of the frame, Fig. 1, it will be seen that the yarn unwound from the supply package S on the spindle 2 of the upper twisting mechanism is fed continuously to the lower twisting mechanism of which the spindle 4 forms one element. For this purpose the yarn is led from the supply package S upwardly over a guide roll 6, thence around and between upper and lower feed rolls 7 and 8, respectively, and through the guide eye 9 to the traveller 10 running on the ring 12 carried by the ring rail 13. This ring is oper-

atively associated with the spindle 4 in the usual manner. In a typical arrangement the lower feed roll 8 only is driven, the upper roll being revolved simply by its contact with the lower roll.

Both of the spindles 2 and 4 are driven at a high speed, and consequently, as the yarn is drawn from the package S it is twisted, the degree of twist depending fundamentally upon the ratio of the speed of the spindle 2 to the feeding speed of the rolls 7 and 8. The lower twisting mechanism operates like any ring twister, taking the yarn from the feed rolls, twisting it and winding it on the spool or bobbin P to produce another thread package. In this mechanism also the amount of twist put into the yarn depends fundamentally on the ratio between the delivery speed of the rolls 7 and 8 and the speed of revolution of the spindle 4. Usually it is preferable to mount a freely rotating traveller 16 on the spindle 2 to be engaged and driven by the yarn in order to reduce the tendency of the yarn to kink as the spindle 2 slows down in stopping the machine to piece up, or for any other reason.

As the yarn travels from the upper twisting mechanism to the lower it may be guided around a roll or rod 14 located in a water pan 15. This operation of wetting the yarn between twisting operations may or may not be used, as desired.

The arrangement just described at the right-hand side of the machine is duplicated at the opposite side, the corresponding parts being designated by the same, but primed, reference characters.

This general arrangement has proved to be exceptionally satisfactory in twisting rayon yarn, sewing thread, and other high twist yarns and threads, due to the fact that the production of the machine can be approximately doubled as compared with that of the ordinary twister frame. It is desirable, however, to maintain constantly a definite speed relationship between each of the upper spindles and its cooperating lower spindle, and an important feature of the present invention resides in a simple reliable

driving mechanism for the spindles which accomplishes this object.

This mechanism includes a driving drum 18 which extends longitudinally of the machine frame, as in twister frames of the usual constructions, and may consist of the common "tin cylinder". Mechanism, not shown, but customarily located at one end of the frame, drives this cylinder. The cylinder 10 is located between and at a lower elevation than the lower pair of spindles 4 and 5, the uppermost surface of the cylinder preferably being slightly below the level of the whirls of the two spindles 4 and 5. A tape 15 or band 20 is driven by the drum 18 and runs in contact with the whirls of all of the spindles 2, 3, 4 and 5 so that it drives them all in the same direction. Starting from the whirl on the spindle 4, it will be seen that 20 the tape travels over a guide roll or tension roll 21 to the drum 18, runs partly around this drum, and thence to a guide pulley 22 located above the drum 18 and between the upper pair of spindles 2 and 3. From the 25 pulley 22 the tape runs around the whirl of the spindle 3, thence across the frame 2 and around the whirl of the spindle 2, back to the guide pulley 22 again, and thence to the driving drum 18. It runs partly around 30 the drum, thence over a second guide or tension pulley 23 to the whirl of the spindle 5, and then across the frame in a straight run to the whirl of the spindle 4.

The tape thus gets a double grip on the 35 driving drum 18, which tends to prevent slippage, and it drives all of the spindles in unison. If the whirls on the spindles are of the same diameter they will all be driven at the same speed. This arrangement usually is 40 preferred, but if desired, the whirls of the upper spindles could be made of a diameter different from that of the whirls of the lower spindles so as to drive the upper spindles at a different speed from that of the lower 45 spindles.

An approximately uniform tension is maintained on the tape by the tension pulleys 21 and 23, these pulleys being pivoted at 24 and 25, respectively, and the swinging frame 50 which carries them being weighted, as in prior constructions, to swing both pulleys inwardly toward the drum 18 and thus to cause them constantly to tighten the tape and to take up slack automatically.

55 The proper guiding of the tape to and around the various whirls and pulleys is facilitated by locating each of the upper spindles 2 and 3 in line, respectively, with the lower spindles at the opposite sides of the 60 frame from them. The two spindles in line are in a plane perpendicular to the axis of the drum 18. This relationship is illustrated in Fig. 2. It will be understood that in Figs. 1 and 2 only those spindles driven by a 65 single tape are shown, but that a twister

frame will include a line of these units all arranged in the same general manner and all driven from the drum 18.

This arrangement not only provides a simple and very reliable drive for the spindles, but it also facilitates the change from a right-hand to a left-hand drive, it simply being necessary to reverse the direction of rotation of the driving drum 18.

If the yarn breaks between any pair of 75 upper and lower spindles, it is desirable to shut down this particular pair without interrupting the operation of the rest of the machine. For this purpose the lower spindle 4 is equipped with a brake lever 28 which rests 80 upon the spindle rail 29 and includes a knee plate 30. The lever carries a brake shoe 31 arranged to engage the upper flange of the whirl of the spindle. A brake mechanism somewhat like that just described is provided 85 for the whirl of the upper spindle 2 and comprises a rocking lever 32 carrying a brake 33 to engage the whirl. In order to operate both brakes simultaneously they are connected together by means of a link 34, bell crank lever 35, and an adjustable link 36. Consequently, when the operator wishes 90 to stop the spindles 2 and 4, she simply presses her knee against the lever 30, thus applying both brakes 31 and 33 substantially simultaneously and bringing both spindles to a stop at approximately the same time. This does not, however, stop the operation 95 of the other pair of spindles 3 and 5, the tape slipping on the whirls of the spindles 2 and 4 so long as they are held against rotation. When the piecing up operation 100 has been completed, the operator releases the knee plate 30 and both spindles 2 and 4 start up simultaneously. The same brake arrangement is provided for each pair of upper and lower spindles in the frame.

The fact that any pair of spindles can thus be stopped to piece up without causing the other spindles to slow down appreciably is 110 an important advantage from an operating standpoint.

In the arrangement shown in Figs. 1 and 2, four spindles are driven by the single tape 20. It is entirely feasible, however, to drive a 115 larger number, and Fig. 3 shows an arrangement in which eight spindles are driven by a single tape. This arrangement in side elevation would look substantially like that shown in Fig. 1. The tape 20' is driven by 120 the drum 18' in the same manner as in the construction shown in Figs. 1 and 2, and a second spindle has been located beside each spindle corresponding to those shown in Figs. 1 and 2. The latter are designated by 125 the same, but primed, numerals used for corresponding spindles in Figs. 1 and 2, and the additional spindles associated with them are indicated at 2a, 3a, 4a and 5a, respectively. This idea has been carried a step further in 130

the arrangement shown in Fig. 4 where two additional spindles are associated with each of the spindles originally used, idlers being located between adjacent spindles to guide the tape properly around the whirls of the respective spindles.

It is obvious that other modifications also may be made without departing from the spirit and scope of the invention.

Having thus described my invention, what I desire to claim as new is:

1. In a twister frame, the combination of two spindles located at opposite sides of the machine frame, two additional spindles located at a higher level and positioned at opposite sides of the frame from each other, a driving drum, and a single tape driven by said drum and running in contact with the whirls of all of said spindles to drive them.
2. A machine according to preceding claim 1 in which each upper spindle is approximately alined in a direction transversely of the frame with the lower spindle on the opposite side of the frame therefrom.
3. In a twister frame, the combination of two spindles located at opposite sides of the machine frame, two additional spindles located at a higher level and positioned at opposite sides of the frame from each other, a driving drum, a single tape driven by said drum and running in contact with the whirls of all of said spindles to drive them, and means for automatically taking up the slack in said tape.
4. In a twister frame, the combination of upper and lower pairs of spindles, the individual spindles of each pair being located at opposite sides of the machine frame, a driving drum located at a lower level than the whirls of said lower spindles, a single tape driven by said drum and running in contact with the whirls of all of said spindles to drive them, and guide rolls located at opposite sides of said drum with their upper edges approximately in horizontal alinement with the whirls of the lower pair of spindles for guiding said tape between the latter whirls and the drum.
5. In a twister frame, the combination of upper and lower pairs of spindles, the individual spindles of each pair being located at opposite sides of the machine frame, a driving drum located between the lower pair of spindles, a guide pulley located between the upper pair of spindles, and a single tape driven by said drum and running in contact with the whirls of all of said spindles and with said guide pulley to drive all of said spindles simultaneously.
6. In a twister frame, the combination of upper and lower pairs of spindles, the individual spindles of each pair being located at opposite sides of the machine frame, a driving drum located between the lower pair of spindles, a guide pulley located between

the upper pair of spindles, a single tape driven by said drum and running in contact with the whirls of all of said spindles and with said guide pulley to drive all of said spindles simultaneously, said tape running from said drum to and partly around said pulley, thence around the whirls of said upper spindles and over the periphery of the pulley back to said drum again, and automatic tensioning rolls positioned to engage said tape at opposite sides of said drum.

HENRY ROBERT MARSH.
